CLAIM

The ornamental design for a cassette player, as shown and described.

DESCRIPTION

FIG. 1 is a front, top and right side perspective view of a cassette player showing our new design;

FIG. 2 is a front elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is a rear elevational view thereof;

FIG. 8 is a perspective view thereof with the cover in an open position; and

FIG. 9 is a perspective view like FIG. 1, the broken line showing of a cassette is environmental only and forms no part of the claimed design.
